US00D666976S

(12) **United States Design Patent**
Gassner

(10) **Patent No.:** **US D666,976 S**
(45) **Date of Patent:** **** Sep. 11, 2012**

(54) **CATHODIC PROTECTION MOLD MAGNET ASSEMBLY**

(75) Inventor: **Gabriel J. Gassner**, Tulsa, OK (US)

(73) Assignee: **Continental Industries, Inc.**, Tulsa, OK (US)

(**) Term: **14 Years**

(21) Appl. No.: **29/399,166**

(22) Filed: **Aug. 10, 2011**

(51) **LOC (9) Cl.** **13-03**

(52) **U.S. Cl.** **D13/149**

(58) **Field of Classification Search** **D13/110, D13/133, 148, 149, 151, 154, 199; 439/331, 439/526, 68, 73, 862; D8/354; 164/54; 228/18, 228/51; 249/97; 285/15, 249, 255, 322, 285/328**

(57) **CLAIM**

The ornamental design for a cathodic protection mold magnet assembly, as shown and described.

DESCRIPTION

FIG. 1 is a perspective view of a cathodic protection mold magnet assembly showing my new design;

FIG. 2 is a top view thereof;

FIG. 3 is a right side view thereof;

FIG. 4 is a left side view thereof;

FIG. 5 is a bottom view thereof;

FIG. 6 is a front view thereof; and,

FIG. 7 is a rear view thereof.

The broken line portion of FIG. 1 showing an exothermic weld mold is included to show unclaimed subject matter only and forms no part of the claimed design.
